LOCK

Edwin W. North, Rockford, Ill., assignor to National Lock Co., Rockford, Ill., a corporation of Delaware

Application April 23, 1931, Serial No. 532,149

13 Claims.

(Cl. 70—53)

This invention relates to locks and more especially to combination locks of a type suitable for use as drawer locks, door locks, etc., and which can be merchandised as hardware.

5 Among other objects the invention aims to provide a practicable and efficient lock controllable both by permutation means and by a key.

School furniture having drawers or lockers assigned to individual pupils should be equipped with 10 locks of the combination type, so as to obviate the inconveniences incident to the use of keys and the frequent losing of keys by pupils. On the other hand it is desirable that all locks in a school building or a given division thereof should be 15 under the control of a key in possession of the schoolmaster, in order that the school authorities may have quick access to all locked drawers and compartments for inspection. Again it is desirable that the locks should be of such character 20 as to permit changing their combinations, so that when a drawer or compartment previously used by one pupil is re-assigned to another it may be under the control of a new combination known only to the occupant and the school authorities.

25 From the foregoing it will be understood that the application of the principle of master key control to locks of the combination type for use in schools, and the incorporation of that principle in a construction of efficient character, and one 30 which will permit adjustment by an authorized person to change the combination of the lock, but which will not be susceptible of such change by the pupil to whom the lock is assigned, are desiderata which have been in mind in evolving the 35 present invention.

Also this invention has been designed with a view to producing a lock structure of practicable design from the standpoint of manufacture, and with a view to producing a construction suitable 40 for application to wooden doors, drawers, etc. in the same manner as ordinary locks merchandised as hardware are applied, i. e. by mortising the lock in the back of the wooden door or door front.

45 Two illustrative embodiments of the invention are shown in the accompanying drawings. For convenience these will be referred to herein as lock A and lock B. These two illustrative locks are similar in fundamentals but embody specifically different features of improvement.

50 It will be understood that the specific construction embodied in each lock is exemplary, and that the details and arrangement of construction may be variously modified.

55 In the drawings, lock A and its parts are shown

in Figs. 1 to 22 inclusive, while lock B and its parts are shown in Figs. 23 to 41.

Fig. 1 is a front elevation of lock A.

Fig. 2 is a side elevation thereof.

Fig. 3 is a vertical section thereof taken longitudinally of the dial axis. 5

Fig. 4 is a cross section on the line 4—4 of Fig. 3, looking in the direction of the arrows.

Fig. 5 is a sectional elevation, the section being taken on the line 5—5 of Fig. 3, looking in the 10 direction of the arrows.

Fig. 6 shows a special key for use in changing the lock combination.

Fig. 7 shows a master key for use in operating a series of locks of the construction of lock A, but 15 having different lock combinations.

Fig. 8 is an enlarged sectional detail view showing a means employed in connection with changing the lock combination.

Fig. 9 is a sectional elevation taken on the line 20 9—9 of Fig. 3, looking in the direction of the arrows.

Figs. 10 to 22 are detail views of various parts, shown in perspective or in elevation.

Fig. 10 is a lock bolt. 25

Fig. 11 is a so-called index finger.

Fig. 12 is a so-called floating member.

Fig. 13 is the first of a set of permutation disks.

Fig. 14 is another of said permutation disks.

Fig. 15 is a small washer element used in connection with a spring which actuates the index finger. 30

Fig. 16 is the so-called key post.

Fig. 17 is a pickup ring with which the permutation disk of Fig. 14 is equipped. 35

Fig. 18 is a spacing washer.

Figs. 19 and 20 are end and side elevations respectively of a positioning member in the lock case.

Figs. 21 and 22 are lock tumblers. 40

Figs. 23 and 24 are side and front elevations of lock B.

Fig. 25 is a vertical central longitudinal section thereof.

Fig. 26 is a sectional elevation taken on the 45 line 26—26 of Fig. 25, looking in the direction of the arrows.

Fig. 27 is the key post of lock B.

Fig. 28 is the master key therefor.

Fig. 29 is a sectional elevation taken on the line 50 29—29 of Fig. 25, looking in the direction of the arrows.

Figs. 30 to 41 are detail views principally in perspective.

Fig. 30 is the lock bolt of lock B. 55

Fig. 31 is its index finger.

Fig. 32 is the accompanying floating member. Fig. 33 is a frame member in the lock housing.

Lock A

Referring first to Figs. 1 to 22 inclusive, the specific construction embodied in illustrative lock

- 15 A is described as follows:

The lock housing comprises the flanged back plate 1 and the front housing member 2 having the protruding cylindrical part 3.

- 20 Fitted to the protrusion 3 is the rotatable dial member 4, which as shown in Fig. 2 may bear a figured dial to be adjusted with reference to an index or pointer at 6.

The dial member 4 and its operating knob 5 are carried on a rotatable sleeve 7 hereinafter referred to as the dial sleeve.

The dial sleeve is rotatably fitted on an inner sleeve 8 extending from a fixed frame plate 9 in the lock housing.

- 25 Slidable in the lock housing is the lock bolt 10 carrying the index finger 11 pivoted thereto at 11a.

- 30 Associated with the lock bolt 10 is a so-called floating member 12 which is movable with the lock bolt 10 in the key-controlled operation of the lock.

- 35 A set of permutation disks, manipulatable by the dial knob, are indicated at 13, 14, 15, the first disk 13 being affixed to the dial sleeve 7, and the other disks 14 and 15 being rotatably mounted on the inner sleeve 8.

A set of lock tumblers are indicated at 16, 17, 18.

- 40 Rotatable within the inner sleeve 8 is the longitudinally slotted key post 19 which when the proper key is inserted can be utilized for operating the lock.

- 45 The lock bolt 10 is operable by the dial knob through the permutation disks and the index finger after working the lock combination or manipulating the disks to a relationship to permit the actuation of the lock bolt. The lock bolt 10 is also operable by the key through the key post and the supplemental or floating member 12.

- 50 In the operation of the lock by the key, the lock bolt 10 and the floating member 12 move as a unit, while in the operation by the dial knob, the lock bolt 10 moves independently or slides relative to the associated floating member.

- 55 As shown in Fig. 10, the lock bolt 10 comprises a head and shank. The head is shown as a laminated body in Fig. 3. In the locked position of the lock bolt, the head of the bolt protrudes through an opening therefor in the back plate flange 1 for engagement in a keeper opening (not shown) of the drawer casing or door jamb for the drawer or door with which the lock is used.

- 60 Referring to Fig. 10 a recess 10a in the head of the lock bolt accommodates the pivoted end of the index finger 11. Another recess 10b in the lock bolt head is provided to clear an element of the floating member hereinafter referred to as the fence, which element is shown at 12c in Fig. 12.

- 65 The lock bolt shank is longitudinally slotted at 10c to receive a stud 12c on the floating mem-

ber, and is longitudinally slotted at 10d to accommodate a fixed guide pin 20 (Fig. 5).

As shown in Fig. 12, the floating member 12 is formed with an opening recessed at 12a for operative engagement by the arm 19a of the key post 19 (Figs. 5 and 16). A projection 12b on the floating member functions as a guide and thrust abutment for the index finger 11 as hereinafter explained. The stud 12c on the floating member passes through the slot 10c of the lock bolt 10. In the locked position, the stud 12c is at the rear end of the slot 10c, i. e. at the bottom end of said slot as the construction is viewed in the drawings.

The floating member 12 is provided with longitudinal slots 12d which receive the fixed guide pins 20. A so-called fence 12e provided by a projection or shoulder on the floating member, cooperates with the lock tumblers, as hereinafter explained, to prevent movement of the floating member except when key-actuated by the requisite key for that purpose.

As shown in Figs. 3 and 5, the lock bolt 10 and floating member 12 are arranged between the back wall of the lock case and the frame plate 9, the floating member 12 being in the rear. One of the two guide pins 20 engaged by the guide slots 12d of the floating member is also engaged by the guide slot 10d of the lock bolt 10. It will be understood that the lock bolt 10 is guided for sliding movement between the floating member 12 and the frame plate 9 and by the sliding of its head in the slot therefor in the back plate flange 1a and the engagement of the slotted shank with one of the guide pins 20; and that the floating member 12 is guided for sliding movement between the lock bolt 10 and the back wall of the lock housing and by engagement of its guide slots 12d with the pins 20.

As shown in Figs. 5 and 9, a wire spring 21 is coiled about a fixed stud or post 22 adjacent to one of the guide pins 20. The short end of this spring bears against the adjacent pin 20, and the long end of the spring bears against the index finger 11 and presses the index finger inwardly or toward the axis of the permutation disks.

Said index finger 11 is formed with a projection 11b adapted to engage notches in the peripheries on the permutation disks when the latter are manipulated to register their notches with said projection. Said projection 11b is also adapted to co-act with the projection 12b on the floating member as hereinafter explained. As shown in Fig. 11, the projection 11b of the index finger is grooved at 11c for engagement by the spring 21.

Referring to the permutation disks, it will be understood that these disks are adapted to pick up one another when the dial knob 5 is rotated, and that by rotating the dial knob in opposite directions, as required to work the combination for which the lock is set to operate, the disks will be adjusted to a relationship whereby their peripheral notches will be in registration and in position to receive the lug 11b of the index finger 11.

The first disk 13, affixed on the inner end of the dial sleeve 7, is shown separably in Fig. 13. Its peripheral notch is indicated at 13a, this notch having a beveled end 13b. The projection 13c on this disk is to pick up the next disk.

In Fig. 3, the disks 14 and 15 are shown as thin perforated rings, and are respectively equipped with adjustable abutments provided by the associated rings 14a and 15a. Each disk 14 or 15 and its associated abutment ring 14a or 15a may be considered as a unit. Fig. 14 shows the disk 14.

having the peripheral notch 14^b and the annular series of perforations 14^c . Fig. 17 shows its abutment ring 14^a having an arm 14^d bent to provide an abutment 14^e and having a terminal 14^f to enter and project through one of the perforations 14^c so as to provide an abutment at the opposite side of the disk 14 .

The illustration of the disk 14 and its associated abutment ring 14^a in Figs. 13 and 16, is likewise illustrative of the next disk 15 and its associated ring 15^a .

Referring to Fig. 3, it will be apparent that the first disk 13 by its projection 13^c (Fig. 13) will coact with the next ring 14 through its abutment ring 14^a , the part 14^e of which (Fig. 17) will be in the path of rotation of 13^c ; also that the terminal 14^f of 14^a protruding through the disk 14 will provide an abutment which in its rotation will engage the abutment ring 15^a of the disk 15 .

In Fig. 3, spacing washers between the disks are indicated at 23 . One of these washers is shown in Fig. 18. It is held non-rotatable by engagement of its lug 23^a in a longitudinal groove 8^a in the sleeve 8 , which groove 8^a is shown in Figs. 9 and 19.

The described construction of the permutation mechanism is exemplary of one appropriate construction of permutation disks adapted for manufacture as metal stampings and suitable for compact assemblage in a small lock construction and of such character as to permit different working combinations for different locks of the same construction, the combination depending upon the angular relationships of the abutment rings 14^a and 15^a to the peripheral notches of the respective disks 14 and 15 . The manufacturer may put out as many different locks of identical construction, each operable with a different lock combination, as the number of changes which can be made in the relationship of the disk 14 and its abutment ring 14^a , multiplied by the number of changes which can be made in the angular relationship of the disk 15 and its abutment ring 15^a . As each disk 14 and 15 has in this instance twenty-two different perforations for engagement by its abutment ring, it follows that there may be four hundred and eighty four different lock combinations for this particular lock, determined by the relationship of the abutment rings to their respective disks. The number of permissible combinations may be multiplied by the use in different locks of first disks 13 having their lugs 13^a at different positions relative to the notch 13^c . Also, after any given lock is assembled, its combination may be changed by a dial adjustment as herein-after explained.

In the specific lock A, a predetermined rotation of the dial knob 5 in a counterclockwise direction will cause the setting of the disk 15 for the unlocking or releasing operation; a predetermined reverse rotation will cause the corresponding setting of the disk 14 ; and predetermined rotation of the knob in the counterclockwise direction will set the first disk 13 , whereupon all the disks will have their peripheral notches in registration to receive the lug 11^b of the index finger 11 as indicated in Fig. 9.

The disks having been thus manipulated to position for registering their notches, the spring-pressed index finger 11 will snap into engagement with the notches. This position of the index finger is shown in Fig. 9. Now by a continued rotation of the dial knob in the counterclockwise direction, the lock bolt 10 will be re-

tracted from locking position by the index finger. In other words, the lock bolt will be drawn back or down through the index finger by the backward pull exerted by the disks, and especially the first disk 13 .

In the retraction of the lock bolt 10 by the dial knob, the floating member 12 remains stationary, being held from retraction by coaction of its fence 12^e with one or more of the lock tumblers $16, 17, 18$, as hereinafter explained. So the lock bolt 10 when dial operated moves independently of the associated floating member. The movement is limited by the stud 12^c , which will engage the head of the lock bolt 10 at the limit of its retracting movement. In this movement, the index finger is carried backward or downwardly past the projection 12^b on the floating member, as will be apparent from Fig. 9. The spring 21 bears slidably against the index finger during this movement, and the projection 12^b on the floating member functions as a guide to prevent any outward movement of the index finger such as to disengage it from the disk notches.

To insure engagement of the index finger with the disk notches when brought into registration with 11^b , and when the dial knob is rotated to effect the unlocking operation or retraction of the lock bolt 10 , the projection 12^b on the floating member is shown having a beveled edge, indicated at 12^g in Fig. 11, for coaction with 11^b to cam it inwardly. This is for the following reason. In the locked condition of the mechanism, the lug 11^b bears against or confronts the projection 12^b as shown in Fig. 5. Now under certain conditions of use, there might be a back thrust or pressure on the lock bolt 10 which would create such a pressure between 11^b and 12^b as to prevent the spring 21 from throwing in the index finger, if the said parts 11^b and 12^b were of such form as to allow binding of the index finger. Therefore, to obviate possibility of such a mishap, the surface 12^g of 12^b engaging the lug 11^b is beveled as shown, so that, after the disk notches have been brought into registration with 11^b , and if there should be any thrust of 11^b against 12^b due to back pressure on the lock bolt, the camming action of 12^b against 11^b will assist the spring in throwing the index finger into engagement with the disk notches.

The lock bolt 10 , having been retracted by operation of the dial knob as heretofore explained, may be protracted or returned to the locking position by a reverse turn of the dial knob. In this operation, the permutation disks rotating in the clockwise direction force the lock bolt forward or up through the thrust communicated through the index finger. By the time the lock bolt reaches its locking position, i. e. the position shown in the drawings, the beveled end 13^b of the notch of the first disk 13 (Fig. 13) engages the lug 11^b of the index finger, and by its camming action throws out the index finger. Then the continued rotation of the dial knob will carry the disk 13 out of registration with the others, thus disestablishing the relationship necessary to permit unlocking.

Reference will now be made to key control of the lock. As before stated, the lock bolt 10 may be actuated by means of a key through the medium of the rotatable key post 19 and the floating member 12 . This operation involves a control by the key tumblers $16, 17, 18$ to permit retraction of the floating member 12 .

As shown in Fig. 5, the floating member 12 is

normally prevented from retraction by the fact that certain of the tumblers would oppose movement of the fence 12^e. In order to permit retraction of the floating member, the tumblers 16 and 17 must be adjusted so as to permit the fence 12^e to enter the slots of all the tumblers. In the specific construction shown in this instance, the tumblers 16 and 17 are constructed to coact with the fence 12^e, these tumblers being normally held by the springs 24 in position to obstruct movement of the fence; while the rearmost tumbler 18 (shown in Fig. 21) is a master key tumbler of such form as never to interfere with the movement of the fence. This master key tumbler 18 has the lateral lug 18^a overlying the other tumblers as shown in Fig. 5, so that by swinging the tumbler 18 to the right the tumblers 16 and 17 will move with it, thus bringing the tumblers to such position that the fence 12^e can move into the slots of the three tumblers, and accordingly permitting retraction of the floating member.

A suitable key is shown at 25 in Fig. 7. This may be a special key for the particular lock, but in this instance it is represented as a master key for operating a number of such locks.

As shown in Figs. 4, 5 and 16, the rotatable key post 19 is longitudinally slotted to receive the key. When the master key 25 is inserted into the key post and pushed back as far as it will go, the key post may be turned to the right (as viewed in Fig. 5), thereby bringing the arm 19^a of the key post into the recessed part 12^a of the floating member. In this movement, the bit 25^a of the master key will coact with the master key tumbler 18 to swing it and the other tumblers into aligned position to release the floating member. The continued turning of the key will cause the key post arm 19^a to coact with the portion 12^b (Fig. 12) of the floating member, thereby retracting the floating member and with it retracting the main lock bolt 10.

This retraction of the lock bolt 10 by the floating member 12 is due to the engagement of the stud 12^c in the rear end of the slot 10^c. In this retracting movement, the index finger 11 moves with the lock bolt 10 and floating member 12 as a unit, the index finger being above the guide and stop projection 12^b of the floating member.

For locking or protracting the lock bolt 10, the key is turned in the reverse direction, thereby pushing up the floating member 12 to its normal position, and this return movement of the floating member is transmitted to the lock bolt 10 through the projection 12^b and the index finger 11. In other words, as the floating member is pushed up or forward, its projection 12^b acting through the index finger 11 pushes the lock bolt 10 to protracted or locked position. In this action there can be no disengagement between the projection 12^b and the index finger, since the lug 11^b of the index finger is confined between the peripheries of the permutation disks and the inner wall of the circular portion of the lock case.

Thus it will be seen that the lock may be operated for unlocking and locking either by manipulation of the dial, or by use of the proper key, preferably a master key. Briefly summarizing, the dial operation is effected by manipulating the dial to work the required combination for releasing the locking mechanism, whereby the permutation disks are brought with their notches in registration in the positions shown in Fig. 9, and the notches of the disks are then engaged by the lug 11^b of the index finger 11 pivotally attached to the lock bolt 10. Then by continuing the rota-

tion of the dial knob 5 in the same direction in which it was last turned for working the combination (in this instance in a counterclockwise direction), the corresponding counterclockwise rotation of the disks will pull back the lock bolt through the connection provided by the index finger 11. Then for locking, the dial knob is rotated reversely or in a clockwise direction so as to protract the lock bolt, and after reaching the protracted or locked position as shown in Fig. 9 a continued clockwise rotation of the dial knob will cause the beveled surface 13^b of the notch in the first permutation disk 13 to exert a cam action against the lug 11^b of the index finger, thus throwing out the index finger from engagement with the permutation disks, and disestablishing the operative combination for unlocking.

In the key operation, the proper key is inserted in the rotatable key post 19, and the key post is turned by the key, which has adjusted the tumblers to release the floating member; and in this turning of the key post the floating member is retracted, thereby drawing back the lock bolt through the connection at 12^c. The index finger 11 positioned as shown in Fig. 5 moves with the lock bolt 10 and floating member 12, and when the key is turned in the reverse direction to advance or shove up the floating member, it pushes up the index finger by the projection 12^b and thereby pushes up or forward the lock bolt to the protracted position shown.

In connection with the key operation, attention is called to the fact that when the rotatable key post 19 is in the neutral position shown in Fig. 5, the slot 19^b in the front end or head of the key post will register with a notch 8^b in the front end flange of the inner sleeve 8 (Figs. 3, 16 and 19). The key 25 is intended to be of such dimension that it cannot be inserted except when 19^b registers with 8^b. This gives the advantage that the key cannot be withdrawn except when 8^b and 19^b are in registration, or in other words, after unlocking the lock by means of the key, the key cannot be withdrawn until the lock is again locked. This insures that the school inspector or other person who unlocks the lock by means of the master key, will leave the lock in operative condition for working by the combination dial.

To permit the school authorities or an authorized person to change the lock combination, the lock embodies a concealed means adapted to be manipulated by means of another special key indicated at 26 in Fig. 6. The means referred to is shown in Figs. 3 and 8. As shown in these figures, the dial member 4, instead of being formed integrally with the dial knob 5, is keyed to the dial sleeve 7 by means of a square pin or detent 27. This detent 27 slides in a slot 7^a in the dial sleeve, and the detent is spring-pressed into engagement with one of a series of notches 4^a in the back face of the dial. As shown, the detent is urged forward by the spring 28 associated with an abutment element 29 engaging the dial sleeve at the rear end of the slot 7^a. The slot 7^a in the dial sleeve is in registration with a slot 8^c in the inner sleeve 8. The special key 26 may be inserted into the key post 19, and when the cam surface 26^a engages the bottom in the slot 19^b (Fig. 16) the projection 26^b of the key will pass up through the slots 8^c and 7^a and engage the detent 27, so that the detent can be pushed backward by the key, thereby disengaging the detent from the rotatable dial member 4. The dial member 4 may then be rotated rela-

tive to the dial knob 5 until another notch 4^a is in registration with the detent.

Thus the dial member 4, instead of being integral with the dial knob, is adjustable thereon to permit an independent rotation of the dial member for adjusting it relative to the first permutation disk 13, thereby changing the combination; the means for this purpose being entirely concealed and manipulatable only by the special key of Fig. 6. The notches 4^a in the back face of the dial member are arranged at uniform intervals, say at every fifth point of the dial. An adjustment of the dial member by rotation in a clockwise direction to change the notch engaged by the detent 27 to the next notch, would result in a corresponding change of five points in the subsequent working of the dial to work the lock combination.

For adjusting the dial to change the lock combination, it is necessary that the dial first be brought to a certain position in reference to the index or pointer 6, and that thereafter the dial knob 5 be maintained exactly in that position during the subsequent adjustment of the dial. This is the position in which the fifth point on the dial registers with the index 6, and in which the slot 7^a in the dial sleeve registers with the slot 8^c in the inner sleeve. Such registration of the slots is of course necessary to permit the actuation of the detent 27 by the key 26. To insert the key 26, the slot 19^b in the key post (Fig. 16) must be registered with the notch 8^b in the front end flange of the inner sleeve, as previously explained. The parts being in this position, then when the key 26 is actuated and manipulated to cause the projection 26^b to engage and push back the detent 27, another projection 26^c on said key will engage a notch 5^a in the dial knob, so that the operator by means of the key may hold the dial knob stationary and in fixed relation to the inner sleeve while the dial member 4 is being adjusted. It will be understood that the dial member may be adjusted five or ten points or any multiple of five points, by rotation either to the right or left, so as to make a corresponding change in the combination required to be worked by the dial for adjusting the permutation disks to the relationship for allowing the unlocking of the lock bolt.

In addition to the features hereinbefore described, attention is also called to the following features embodied in lock A.

This lock is exceedingly compact. Its compactness is obtained in part by reducing the thickness of the shank of the lock bolt 10 as compared with the head of said lock bolt and in part by arranging the index finger 11 to the left of the tumblers and near the head of the lock bolt and partially within the head. The construction permits incorporation in a lock of such small dimension lengthwise of the lock bolt as to permit use of the lock in a comparatively shallow drawer.

The back plate 1 has the rearwardly extending embossed portion 1^b, providing a socket to receive the front housing member 2, and permitting the mechanism to be housed partially behind the flat portion 1 of the back plate. This feature makes it possible to mortise and mount the lock in a thinner drawer panel than would be possible without this embossing of the back plate. Another purpose of the embossing of the back plate is to make this lock so it will interchange and fit the same sized mortise used with certain ordinary drawer locks.

Another feature to which attention may be called is that the key cylinder or inner sleeve 8

is unitary with and extends forwardly from the frame plate 9 which has three feet 9^a bearing against the back plate, (Figs. 3, 19 and 20) whereby the key cylinder is properly centered and all the parts are held in their proper relations. Also the frame plate 9 spaced from the back plate by the legs 9^b insure freeing the tumblers 16, 17, 18 from any pressure. In other words, in case of any warping or expansion action of the permutation disks, such action will not be permitted to bind the lock tumblers.

Lock B

Referring to Figs. 23 to 41, lock B, being basically similar to the other, may be briefly described as follows:

The lock housing comprises the flanged back plate 101 and front housing member 102 attached thereto by suitable screws 103.

In the housing is the slidable lock bolt 110 the head of which protrudes through a slot therefor in the back plate flange. This lock bolt shown in Fig. 30 has the studs 111 and 112. The index finger 113 shown in Figs. 29 and 31 is pivoted on the stud 111 and is pressed inwardly by the spring 114. The index finger has the hook or lug 115 to engage the notches of the permutation disks.

Immediately in front of the lock bolt 110 is the floating member 116 having the slots 117 and 118, the fence 119, and the guiding and stop projection 120. As shown in Figs. 26 and 32, the floating member is formed with the recessed part 121 for coaction with the arm of the rotatable key post.

The stud 111 of the lock bolt 110 passes through the slot 118 of the floating member, and the index finger 113 is pivoted to the stud 111 at the front side of the floating member, as will be apparent from Fig. 29.

The floating member is normally held from retraction by the lock tumblers. When retracted, it is guided in its movements by the fixed studs 122 and screw 103, the screw 103 being in the guide slot 117.

The lock bolt 110 is guided in its movements by its head slidably fitted in the slot therefor in the back plate flange, and by its pin and slot connection 111, 118 with the floating member, and by engagement of the shank of the lock bolt with one of the studs 122.

Immediately in front of the floating member is the fixed frame plate 125 attached to the back plate in spaced relation thereto by appropriate studs and screws. This frame plate, shown in Fig. 33, has the forwardly extending sleeve 126 with the slots 127.

The front housing member 102 has a protruding portion 128 provided with a rigid sleeve 129 within the housing, the sleeve 129 being concentric with the sleeve 126 extending from the frame plate 125.

Rotatably fitted within the sleeve 129 and to the sleeve 126 is the dial sleeve 130 provided with the knurled knob 131 and figured dial member 132 adapted to be read with reference to a fixed index point 133 on the housing member.

The dial sleeve has affixed on its inner end the first disk 135 of a set of permutation disks similar to those already described with reference to lock A. These permutation disks are respectively designated 135, 136 and 137. The disks 136 and 137 are rotatably mounted on the sleeve 126. Said disks 136 and 137 are respectively equipped with adjustable abutment rings 136^a and 137^a of 75

the character already described. One of such disks and its abutment ring are shown in Figs. 37 and 35.

The permutation disks are spaced by washers 5 138 and 139. Preferably these washers or at least one of them are formed as shown in Figs. 29 and 34 to provide the ward 139^a. In slipping such washers over the sleeve 126, the ward 139^a is 10 permitted to pass within the sleeve by virtue of its slots 121. The purpose of the ward is to prevent picking the key-controlled lock mechanism. The spacing washers may however be of the form shown in Fig. 36.

The rotatable key post 140 has the head 141 and 15 the arm 142. This post is longitudinally slotted to receive the key 143 shown in Fig. 28.

Tumblers controlled by the key are shown at 20 150, 151 and 152. These tumblers cooperate with the fence 119 of the floating member 116 to prevent retraction in the manner already explained 25 in connection with lock A.

The individual tumblers are shown in Figs. 39, 40 and 41. Springs for holding the tumblers 150 and 151 in their normal positions are indicated at 25 153.

In this instance, only the tumbler 150 obstructs 30 the movement of the floating member. It may be termed a change key tumbler. The next tumbler 151 is a sub-master key tumbler, having a projection 151^a overlying the tumbler 150, so that by rocking the tumbler 151 to the right the tumbler 150 will be adjusted to allow a free passage 35 of the fence 119 into its gateway. The third tumbler 152 is a grand master key tumbler, the projection 152^a of which overlies the two other tumblers, so that by rocking the tumbler 152 the tumbler 150 will be adjusted to the unlocking position.

The operation is as follows: The lock bolt is 40 locked both by the permutation means and by the key-controlled means, as in the case of the lock A first described. It may be unlocked and retracted and again protracted and locked by dial manipulation in substantially the manner already 45 described, except that in this case the initial dial movement and the dial movement to retract the lock are clockwise. It will be understood that the dial is manipulated to work the combination required for releasing the lock. This brings the permutation disks to a relation in which their peripheral notches register, in position to be engaged 50 by the lug or hook 115 of the index finger 113 as shown in Fig. 29. Then, as the clockwise rotation of the dial knob is continued, the lock bolt 55 110 is drawn back or down by the index finger. In this operation the index finger moves inside the guide and stop projection 120 of the floating member. To throw out the lock bolt, the dial knob is turned reversely or counterclockwise and 60 when the notches of the disks move past the projection 120 the camming action of the bevel 135^a of the notch of the first permutation disk 135 will throw out the index finger. Thus the lock 65 is restored to the combination-locked condition.

65 For unlocking by key operation, the proper key is inserted to adjust the tumblers so as to allow the fence 119 of the floating member to enter the gateways of the tumblers. It will be understood that as the key is turned it turns the key post 140 so that the key post arm 142 coaxing with the floating member 116 at the recessed part 121, as shown in Fig. 26, will draw back the floating member and with it retract the lock bolt 110. In this movement, the index finger 113 is 70 carried with the lock bolt 110 and floating mem- 75

ber 116, said finger confronting or bearing against the projection 120. When the key is turned in the reverse direction, it returns the floating member to its normal position, and in this motion the projection 120 will, through the index finger, push 5 out the lock bolt to its protracted or locked position.

It will be understood that with the tumblers shown in Figs. 39 to 41, the lock could be operated by either a special key for the particular 10 lock, or by a grand master key controlling the tumbler 152, or by a sub-master key controlling the tumbler 151; the sub-master key being adapted for operating only as many as have identical 15 tumblers 151, for instance the locks for a certain division of a school, and the special key being adapted only for an individual lock, it being assumed that the tumbler 150 will be different for every individual lock.

In this instance the key 143 shown in Fig. 28 20 is a grand master key. When inserted in the key post and pushed all the way in, and when the key is turned in a direction to operate the floating member, the bit 143^a of the key will actuate the grand master key tumbler 152. The notch 143^b 25 enables the key to clear the ward 139^a.

To permit changing the lock combination, the dial member 132 has notched engagement with a radially displaceable pin or detent 155 upheld by the leaf spring 156. The pin or detent 155 is a 30 square block radially slidable in a slot in the dial sleeve. In a commercial lock the pin 155 is quite small and would not ordinarily be observable. Apparently it is an integral part of the dial knob. The head 141 of the rotatable key post 35 has a recess 151. The key post may be turned to register the recess 151 with the pin 155. Then by means of the point of a penknife the pin 155 can be depressed into the recess 151, and the dial 40 can be independently turned five points or any multiple of five points to engage another notch of the dial with the pin 155. This changes the relationship of the dial to the dial knob and consequently the relationship of the dial to the first permutation disk, accordingly changing the combination required to be worked for unlocking the lock. The lock must be in the unlocked position 45 in order to permit the change in the combination.

The spring 160 in Figs. 29 and 26 bears against the lock bolt 110 and is adapted to engage a notch 50 161 in the floating member to hold the same steady. When the floating member is retracted, the spring engages the other notch 162. In the protracted position of the lock bolt 110, the spring 160 also engages its notch 163, and when the lock bolt is retracted the spring engages its notch 164.

Obviously the invention is not limited to the specific embodiments shown. Moreover it is not indispensable that all of the features of the invention be used conjointly, since various features may be advantageously used in various combinations and subcombinations.

I claim:

1. A combination lock having a rotatable dial 65 knob, a rotatable key post concentric with said knob, permutation disks operable by the dial knob, a lock bolt, a member operable by the key post for operating said lock bolt, and means cooperable with the disks for operating the lock bolt by the 70 dial knob, said means comprising an index element pivotally connected to the lock bolt and normally held by said disks in cooperative engagement with an abutment on said member to establish an operative connection between said 75

- member and lock bolt but displaceable from such engagement to disestablish such connection when the disks are manipulated to establish condition for operating the lock bolt by the dial knob.
- 5 2. A combination lock having a dial-operable lock bolt, dial-operable permutation means controlling the dial operation of said lock bolt, a key-operable member for operating said lock bolt independently of the dial operation, said lock bolt and member movable as one piece in the operation of the lock bolt by the key, and means controlled by said permutation means for establishing an operative connection for dial operation upon a predetermined setting of the permutation means 10 and for establishing an operative connection for key operation when such predetermined setting of the permutation means is disestablished.
- 15 3. A combination lock having a rotatable dial knob, permutation disks manipulatable thereby to a predetermined relationship, a lock bolt operable by the dial knob when such relationship is established, a rotatable key post, a floating member operable directly by said key post, said member being directly connected with the lock bolt in a manner to render the lock bolt retractile by said member and independently retractile, tumbler means normally preventing retraction of said member and operable to permit such retraction when the key post is rotated by a proper 20 key therefor, and means controlled by said permutation disks rendering said lock bolt operable by the dial knob when a predetermined relation of the permutation disks is established and establishing a connection for protracting the lock bolt by said member when such predetermined relationship is disestablished.
- 25 4. A lock having a lock bolt, a floating member, said lock bolt and floating member being adjacent and having identical motions, there being a connection between said lock bolt and floating member for retracting said lock bolt by retraction of said floating member and for permitting independent operation of the lock bolt, a rotatable operating member, notched permutation disks operable one by another, one of said disks being connected to said rotatable member, said lock bolt having an index finger engageable with the notches of said disks when registered therewith, whereby said lock bolt can be operated by said rotatable member through the permutation disks and index finger, key-operable means for operating said floating member, said lock bolt and floating member and index finger being movable as one piece in the retraction of the lock bolt by the floating member, and said floating member having means cooperable with said index finger whereby to protract the lock bolt by the protracting movement of the floating member.
- 30 5. A lock having associated protractile members one operable by the other and also independently operable, one of said members being a lock bolt, a rotatable tubular operating member, notched permutation disks operable one by another, one of said disks being connected to said rotatable member, one of said protractile members having an index finger engageable with the disk notches when registered therewith, whereby the member having such index finger can be operated by said rotatable member through the permutation disks and index finger, a rotatable key post enclosed by said rotatable tubular member for operating the other protractile member, and means on said other protractile member with which said index finger when disengaged 35 from said disk notches cooperates for establishing operative connection between said protractile members.
- 35 6. A lock of the character described in claim 5 in which the index finger is pivoted to the protractile member carrying it and has a lug or hook to engage the disk notches, and the other protractile member has a projection cooperable with said index finger as a thrust abutment in the operation of one protractile member by the other and serving as a guide post which the index finger moves past when the protractile member carrying such index finger is independently operated.
- 40 7. A combination lock having a lock bolt, an index finger pivoted thereto, dial operated means including notched permutation disks manipulatable to register their notches for engagement by said finger whereby said lock bolt can be operated through said disks and finger, a floating key-operable member, and a rotatable key post concentric with said dial operating means to receive the key for operating said floating member, there being a direct connection between said lock bolt and member for retracting the lock bolt 45 by retraction of the floating member and for permitting independent dial operation of the lock bolt, said floating member having a projection within which the index finger moves in the dial operation of the lock bolt and which affords an abutment for said index finger when it is held out by the unnotched peripheries of the disks, whereby the lock bolt can be protracted by protraction of the floating member.
- 45 8. A lock having a lock bolt, a floating member, there being a direct connection therebetween for retracting said lock bolt by retraction of said floating member and for permitting independent operation of the lock bolt, a rotatable operating member, notched permutation disks operable one 50 by another, one of said disks being connected to said rotatable member, said lock bolt having an index finger engageable with the notches of said disks when registered therewith, whereby said lock bolt can be operated by said rotatable member through the permutation disks and index finger, key-operable means for actuating said floating member, tumblers cooperating directly with said floating member to secure it in fixed position, said tumblers being operable to permit actuation of the floating member when the key-operable means is operated by a proper key, and said floating member having means cooperable with said index finger whereby to protract the lock bolt by the protracting movement of the floating member.
- 55 9. In a combination lock, the combination with encased mechanism including permutation disks and a dial sleeve having one of said disks attached thereto, of a dial member on said sleeve 55 rotatable therewith, said dial member having notches, said dial sleeve having a longitudinal slot, a spring-pressed detent working in said slot and engaging one of said notches, an inner sleeve having a slot registered with the slot in said dial sleeve, and a slotted key post rotatably mounted in the inner sleeve, the construction permitting disengagement of the detent from said notch by means of a tool inserted through the key post and engaging said detent through said slots, 60 whereby the dial member can be adjusted to permit a different notch to be engaged.
- 60 10. A combined combination and key lock having a plurality of disk tumblers operable one by another, a rotatable operating member for one 65

- of said tumblers, a lock bolt, a key-operable member associated with said lock bolt as a carrier therefor, said lock bolt and associated member having identical motions and having directly co-
5 acting means whereby the said member when retracted retracts the lock bolt therewith, said means permitting independent retraction of the lock bolt, and an element connected to the lock bolt and normally held by said disk tumblers in
10 engagement with an abutment on said key-actuated member, whereby said member when protracted protracts the lock bolt therewith, said disks adapted when brought to a predetermined relationship to release said element from said
15 key-actuated member and said element when so released establishing an operative connection between the lock bolt and rotatable operating member whereby the lock bolt can be retracted and protracted by said rotatable member.
20 11. A lock having a key-actuated member, tumbler means requiring insertion of a proper key to actuate said member and coacting with said member to lock it in protracted position when the key having actuated it to such position
25 is withdrawn, a lock bolt directly engageable with and retractable by said member and also independently retractable, an element connected to the lock bolt and normally engaged by said member for imparting protractive movement of
30 said member directly to the lock bolt, disk tumblers operable one by another and normally holding said element in engagement with said member, and a rotatable operating member connected with one of said disk tumblers, said disk tumblers
35 having notches adapted when brought into registry to be engaged by said element, thereby freeing the lock bolt from said key-actuated member and operatively connecting it with said rotatable operating member so as to be retracted and pro-
40 tracted thereby.
12. A lock having parallel members movable as
one piece in a right line to locking and unlocking position, a rotatable operating member, disk tumblers controlled thereby, means controlled by said tumblers for establishing operative connection between said rotatable member and one of said parallel members whereby to move the latter to and from locking position, key-controlled means for operating the other of said parallel members, one of said parallel members adapted to operate the other and said other being independently operable, the said means which is controlled by the tumblers functioning as an operative connection between said parallel members when one is operated by the other, one of said parallel members being a lock bolt.
13. A combined combination and key lock having a plurality of disk tumblers operable one by another, a rotatable operating member for one of said tumblers, a lock bolt, a key operable member associated with said lock bolt, there being provision for insertion of the operating key coaxially with said rotatable operating member, said lock bolt and key operable member having directly coacting means whereby said member when retracted retracts the lock bolt therewith, said means permitting independent retraction of the lock bolt, and an element connected to the lock bolt and normally held by said disk tumblers in engagement with an abutment on said key-actuated member, whereby said member when protracted protracts the lock bolt therewith, said disks adapted when brought to a predetermined relationship to release said element from said key-actuated member and said element when so released establishing an operative connection between the lock bolt and rotatable operating member whereby the lock bolt can be retracted and protracted by said rotatable member.

EDWIN W. NORTH. 40

CERTIFICATE OF CORRECTION.

Patent No. 2,002,453.

May 21, 1935.

EDWIN W. NORTH.

It is hereby certified that error appears in the printed specification of the above numbered patent requiring correction as follows: Page 7, first column, line 11, claim 2, before "and" insert the words a key post, said member directly operable by said key post and said lock bolt directly operable by said member,; and line 53, claim 4, for "bolts" read bolt; and that the said Letters Patent should be read with these corrections therein that the same may conform to the record of the case in the Patent Office.

Signed and sealed this 9th day of July, A. D. 1935.

Bryan M. Battey

(Seal)

Acting Commissioner of Patents.
